UNITED STATES PATENT OFFICE.

ROBERT H. STOCKTON, OF ST. LOUIS, MISSOURI, ASSIGNOR TO MAJESTIC MANUFACTURING COMPANY, OF ST. LOUIS, MISSOURI, A CORPORATION.

COOKING-RANGE.

933,498.

Specification of Letters Patent.

Patented Sept. 7, 1909.

Application filed January 30, 1909. Serial No. 475,112.

To all whom it may concern:

Be it known that I, ROBERT H. STOCKTON, a citizen of the United States of America, residing at the city of St. Louis, in the 5 State of Missouri, have invented certain new and useful Improvements in Cooking-Ranges, of which the following is a full, clear, and exact description, reference being had to the accompanying drawings, forming 10 part of this specification.

My invention relates to a cooking range and it has for its object to so construct a cooking range having a surmounting back plate as to provide for an unobstructed top 15 surface of the range top adjacent to the back plate and between the shelf or warming closet supports in order that the range top may be more readily and efficiently polished at its surface immediately in front of 20 the point at which the back plate is located. Ranges as heretofore made and in which provision is made for the attachment of a back plate above the range top have commonly had cast upon the range tops posts or 25 upright lugs for the attachment of the back plate, and when such posts or lugs are present upon the range top it is difficult to polish the rear portion of the range top in preparing 30 it for the market, while by my improvement these posts or lugs are entirely dispensed with and the entire top surface that appears 35 in front of the back plate when the range is completed may be readily polished, with the result of greatly enhancing the appearance of the top of the range.

Figure I is a rear elevation of a range containing my improvement, the range being shown partly in full lines and partly in dotted lines. Fig. II is an enlarged rear elevation partly broken out of the top of my range and the lower portion of the back plate surmounting said top. Fig. III is in part 40 an enlarged elevation and in part a vertical section of the rear portion of the range top and the lower portion of the back plate surmounting said top.

In the accompanying drawings, 1 designates the body of a range and 2 the top surmounting said body and which is provided 45 with a back flange 3. At the junction of the horizontal portion of the top of the range and its back flange is a recessed seat 4 that extends continuously from end to end in said back flange and is adapted to receive the 50 back plate that surmounts the range top.

5 are posts or upright lugs cast integral with the back flange of the range top and which extend above the recessed seat 4, as seen in Figs. II and III, thereby serving to partly close said recessed seat and to form 60 back walls therefor.

6 designates a back plate of the range which extends vertically from the range top. This back plate is provided at its lower edge with a curled bead 7 that occupies the recessed seat 4 in the back flange of the range top and is held in position in said seat and against its front wall by the upright lugs 5. When this curled bead is introduced into the position just stated, it becomes tightly 70 wedged therein due to its being of curled form and having a natural resiliency therein due to the curling of the metal of which the back plate is produced. The back plate may be sustained in an upright position by any 75 suitable means and it is preferably attached to brackets, one of which is shown at 8 Fig. III, and which also serve as supports for a shelf or warming closet located above the range top in a manner common to cooking 80 ranges.

I claim:—

1. A cooking range, comprising a flanged top having a recessed seat at the top of its rear flange, lugs projecting upwardly from 85 the rear flange at the back of said recessed seat, and a back plate having its lower edge located in said recessed seat in front of said lugs.

2. A cooking range, comprising a flanged 90 top having a recessed seat at the top of its rear flange, lugs projecting upwardly from the rear flange at the back of said recessed seat, and a back plate having its lower edge located in said recessed seat in front of said 95 lugs; said back plate being provided at its lower edge with a bead.

3. A cooking range, comprising a flanged top having a recessed seat at the top of its rear flange, lugs projecting upwardly from 100 the rear flange at the back of said recessed seat, and a back plate having its lower edge located in said recessed seat in front of said lugs; said back plate being provided at its lower edge with a curled bead.

R. H. STOCKTON.

In the presence of—

W. M. H. SCOTT,
EDNA B. LINN.
